(57) **CLAIM**

The ornamental design for a BBQ cleaning brush, as shown and described.

DESCRIPTION

FIG. 1 is a front, top perspective view of a BBQ cleaning brush, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view taken from line 9 in FIG. 1;

FIG. 10 is an enlarged view taken from line 10 in FIG. 1; and,

FIG. 11 is an exploded view of the BBQ cleaning brush. The dashed broken lines in the figures illustrate portions of the BBQ cleaning brush that form no part of the claimed design. The dash-dot-dash broken lines in FIGS. 1, 9 and 10 depict the bounds of the enlarged views and form no part of the claimed design.
